US0D1098000S

(12) **United States Design Patent** (10) **Patent No.:** **US D1,098,000 S**
(45) **Date of Patent:** **** Oct. 14, 2025**

(54) **BATTERY**

(71) Applicant: **Shenghuan Lin**, Shenzhen (CN)

(72) Inventor: **Shenghuan Lin**, Shenzhen (CN)

(**) Term: **15 Years**

(21) Appl. No.: **29/939,740**

(22) Filed: **Apr. 29, 2024**

(30) **Foreign Application Priority Data**

Nov. 7, 2023 (CN) 202330724035.X

(51) **LOC (15) Cl.** **13-02**

(52) **U.S. Cl.**

USPC **D13/103**

(58) **Field of Classification Search**

USPC D13/103, 104, 107, 108, 110, 112, 118,

D13/119, 184, 199

CPC H02J 7/00; H02J 7/0042; H02J 7/0044;

H02J 7/0047; H02J 7/0045

See application file for complete search history.

(57) **CLAIM**

The ornamental design for a battery as shown and described.

DESCRIPTION

FIG. 1 is a perspective view of a battery showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion 9 shown in FIG. 1. The dash-dash broken lines in the drawings depict portions of the battery that form no part of the claimed design. The dot-dash broken lines represent boundaries of the enlarged portions and form no part of the claimed design.

1 Claim, 9 Drawing Sheets
